(57) **CLAIM**

The ornamental design for a foot pedal, as shown and described.

DESCRIPTION

FIG. 1 is a perspective view of a foot pedal of our new design;

FIG. 2 is a top plan view of the foot pedal of FIG. 1; FIG. 3 is a left side elevation view of the foot pedal of FIG. 1;

FIG. 4 is a right side elevation view of the foot pedal of FIG. 1;

FIG. 5 is a rear elevation view of the foot pedal of FIG. 1; FIG. 6 is a front elevation view of the foot pedal of FIG. 1; and,

FIG. 7 is a bottom plan view of the foot pedal of FIG. 1. The broken lines form no part of the claimed design.

1 Claim, 7 Drawing Sheets(56)
